UNITED STATES PATENT OFFICE

CLARENCE E. RILEY, OF SOUTH PASADENA, CALIFORNIA

PHOTOENGRAVER'S GLASS DIPPING RACK

Application filed October 21, 1930. Serial No. 490,157.

This invention consists in the provision of means adapted for use in cleansing glass plates preparatory to making negatives or positives for use in the photo-engraving art.

5 It is necessary to cleanse such plates prior to coating them with the sensitive solution, and it is customary to effect such cleansing by placing the plates, one upon another in a bath of nitric acid; and then removing the 10 plates one by one for drying and for use. Such work is tedious and slow and likely to cause the operator to burn and discolor his hands with the acid, and is also inconvenient and accompanied by frequent breakage 15 of plates.

An object of this invention is to avoid the inconvenience, injury and loss heretofore common to the work of washing glass plates with acid or other cleansing liquids.

20 The invention broadly includes a crate comprising a head grooved on its under face, a floor grooved on its upper face, a frame holding the head spaced above the floor with the grooves of the floor and head in parallelism below and above a plate accommodating 25 space, to hold the lower and upper edges of the plates to be washed, and means for handling the crate.

An object of the invention is to provide a 30 light, simple, rigid and strong metallic crate adapted to the purpose; and with this object in view, I have produced grooved plaques, each comprising slat stampings secured together by wire and arranged so that the wire rigidly holds such plaques in parallelism, one above the other, and form the wire into 35 loops extending above the top plaque to unitedly serve as a bail by which the crate and its load of plates can be lifted and 40 handled.

With a view to convenience of construction, I form the wire into four sections and apply an intermediate length of each section as a cross-bar, there being thus formed, four 45 cross-bars which are threaded through their respective ends of the plaques; other portions of such wire sections being arranged as frame standards, braces and loops, to complete the frame, and I also provide side bars 50 for each plaque and secure the same in place

by portions of the wire sections threaded therethrough.

An object is to provide a light, strong, rigid rack having plate holding grooves 55 open at one end so as to allow the glass plates to be shoved into the rack at one end, and to so construct the rack that the frame at the other end of the rack will form a stop for the plates, but will leave such other end of the plate free to be pushed upon by the 60 operator, for sliding the plates out of the receiving ends of their grooves respectively.

An advantage is that the glass plates are held upright, free from face contact with each other so that the cleansing liquid of the 65 bath has direct and free contact with the entire plate surface on both sides, thus insuring perfect cleansing.

Another advantage is that by the arrangement allowing the plates to be slid into and 70 out of the grooves, free from face contact with each other, the danger of scratching the faces of the plates and of breakage and of chipping the corners of the glass, is 75 avoided.

Another advantage is gained through avoiding loss of camera exposures of dirty 80 glasses.

Another advantage is the saving of time by lessening the handling of the glass plates.

The invention includes the crate or rack and the parts, combinations of parts that go to make up the same.

Other objects, advantages and features of 85 invention may appear from the accompanying drawing, the subjoined detailed description and the appended claims.

The accompanying drawing illustrates the invention.

Figure 1 is a perspective view of a plate 90 dipping rack made in accordance with this invention and ready to receive photographic glasses for dipping and cleansing.

Fig. 2 is a perspective view of the slat-holding frame disassembled.

Fig. 3 is a fragmentary detail of one of the floor slats detached.

Fig. 4 is a fragmentary view of a stamping for making one of the slats.

Fig. 5 is a fragmentary end view of the 100

dipping rack shown in Fig. 1; fragments of three photographic glass plates being shown in place.

Fig. 6 is a fragmentary side elevation of one of the floor slats.

Fig. 7 is a fragmentary side elevation of one of the head slats.

It is understood the floor slats and head slats are all alike.

10 The floor 1 and head 2 are grooved plaque-like bodies shown as assembled of slats, side bars and cross-bars connected together in parallel horizontal planes, one below the other, with the grooves arranged in 15 pairs open toward each other.

The slats 3 of both the floor and head are alike throughout, being bent-up sheet metal stampings as indicated in Figs. 3 and 4, where a runner and a rib are united at a 20 right angle to constitute the angle bars in each of which the runner ends extend in curls on the side of the runner opposite to the rib so as to constitute hubs through which the cross-bars extend. The slats 3 25 of the floor, are thus strung on the cross-bars 4, 5, and the slats 3 of the head are strung on the cross-bars 6, 7.

The floor is provided with side bars 8, 9, through which the floor cross-bars 4, 5, are 30 extended, and the head has side bars 10 and 11, through which the cross-bars 6, 7, extend.

The side bars and slats of the floor are thus united by the cross-bars 4, 5, and the side bars and slats of the head are secured 35 together by the head cross-bars 6, 7.

Said cross-bars 4, 5, 6, 7, are parts of a wire skeleton frame formed of four bent wire sections 13, 14, 15, 16.

40 The end brace section 13 comprises the floor cross-bar 4, the upright standards *a* and *b* and the diagonal end brace *c*. The U section 14 comprises the floor cross-bar 5 and two uprights *d*, *e*.

The diagonal longitudinal U brace section 45 15 comprises the head cross-bar 7 and the longitudinal diagonal braces *f* and *g*.

The first floor side bar 8 is provided at one 50 end with three holes 4', *c'* and *f'*, that form seats to accommodate the cross-bar 4, and the hook ends of the cross and side stays *c* and *f*; and said side bar 8 is provided at the other end with only one hole 5', through which hole the second floor cross-bar 5 55 extends.

The second floor side bar 9 is provided at one end with two holes *b'* and *g'* for the cross-bar 4 and the hook *h* of the diagonal side stay *g*, and is provided at the further 60 end with the hole *e'* for the cross-bar 5.

The head side bar 10 has at one end two holes *a'* and *g'* to respectively seat the hook *a''* of the standard *a* and the head cross-bar 6, and is provided at its further end with 65 three holes *f''*, *d'* and *h'*, to seat the cross-

bar 7, the hook end *d''*, of the standard *d* and the hook end *i* of the bail loop 19.

The head side bar 11 has at one end two holes *j*, *k*, to seat the bend 20 between the standard *b* and end brace *c*; and has at its 70 further end the three holes 21, 22 and 23 to seat the cross-bar 7, the hook 24 of the upright *e*, and the hook 25 of the loop member 26 of the bail 17.

The slats for the floor and the head are 75 alike and in practice the stampings shown in Fig. 4, will first be made, comprising the runner 27 and the rib 28 of different lengths, the runner having end extensions 29 curled away from the rib to form the hubs 30 80 through which the cross-bars will be strung in the course of assembly.

The frame sections 13, 14, 15, and 16 are pieces of pliable and malleable wire of a suitable character resistant to erosion of 85 nitric acid, and are threaded through, and bent to the side bars as shown and in a manner that will be readily understood by one skilled in the wire working art.

The hook ends of the wire sections afford 90 a convenient means of fixing the ends of the sections to their seats to which they are secured, but it is understood that welding, brazing or soldering may be employed within 95 the knowledge of the workman, without departing from the spirit of the invention.

In practical use, the operator will insert the plates in the appropriate groove pairs and will then lift the loaded crate from its support, not shown, and dip it into the 100 cleansing bath, and when the cleansing has been completed, will dip the crate in a rinsing bath of clear water and will then lift the crate and its load of cleansed plates to a support, and the plates are removed one by one at the open end 31 of the crate, and coated with albumen while wet, and will then be set aside to dry and to be coated with the film as needed.

The upwardly extending wire loops 17 and 110 19 are bent over the top member or head 2 so as to be readily grasped by the fingers of one hand, and both loops being formed of a single wire, the middle of which forms the cross-bar at one end of the head, while the outer ends of such wire are hooked to the other end of the head, the crate is securely supported by the bail for handling the loaded 115 crate.

I claim:—

1. The combination with slats comprising ribs and runners provided with hubs, of cross-bars extending through the hubs to hold the slats together to form a grooved member of a plate holding rack.

2. The combination with slats and side bars, of four sections of wire, each provided with hooks at its ends for engaging two side bars, and forming cross-bars between such side bars; the side bars and slats be-

ing provided with orifices and the cross-bars being strung through the orifices to hold the bars and slats together, some to form a floor and others to form a head; the slats being provided with ribs and runners to form grooved ways for the floor and head; intermediate portions of the wire sections extending between the floor and head to space the floor and head apart; and loops being formed in one of the wire sections to form a bail for handling the crate.

3. In a glass holding crate comprising slats formed of ribs and runners, a wire threaded through the slats and bent to form parts of the crate frame.

In testimony whereof, I have hereunto set my hand at Los Angeles, California, this 14th day of October, 1930.

CLARENCE E. RILEY.
